UNITED STATES PATENT OFFICE.

KARL KIEFER, OF CINCINNATI, OHIO.

FILLING MACHINE.

Application filed June 12, 1920. Serial No. 388,588.

To all whom it may concern:

Be it known that I, KARL KIEFER, a citizen of the United States, residing at Cincinnati, in the county of Hamilton and State 5 of Ohio, have invented a new and useful Improvement in Filling Machines, of which the following is a specification.

My invention pertains to apparatus for filling narrow necked or wide mouthed bottles or cans with liquid or semi-liquid substances, such as preserves or chili-sauce, without, however, being limited to any particular vessel or material.

I attain the object of my invention by the 15 mechanism illustrated in the accompanying drawing, in which—

Fig. 1 is a sectional end elevation of the filling machine, the section being on the vertical plane of the line 1—1 of Fig. 3, but 20 after rotation 90° therefrom;

Fig. 2 is a partial cross-section, corresponding to that of Fig. 1, enlarged, showing the valve mechanism;

Fig. 3 is a plan view of the machine with 25 the upper part removed on the plane of the line 3—3 of Fig. 1; and

Fig. 4 is a plan view of a valve detail.

In Figs. 1 and 3, A is the table plate with a central bearing 2 in which a shaft 3 revolves, the lower part of this shaft having a 30 thread which is engaged by the hand wheel 4 for the raising and lowering of the shaft 3. A bevel gear 5 engages by means of a key and slot 3' with the shaft 3, and by 35 means of the driving mechanism and pulley 6, shown by dotted lines in Fig. 1, the shaft 3 is rotated. The center shaft 3 with its threaded part revolves in the lower bearing 10, attached to the bottom frame B of the 40 frame work.

Next to the center bearing 2 is a sprocket wheel 8 engaging a flexible chain 7, plainly visible in Fig. 3. This driving sprocket engages by means of a key to the slot 3' of the 45 shaft 3. An idler 8 Fig. 3, forms the return for the endless flexible chain.

Flexible chain 7 carries a number of trays 9 and these trays are to receive the bottles or cans which are to be filled, as shown in 50 Fig. 1. Mounted upon the frame A as shown in Figs. 1 and 3, are four posts 12, 12', 12'' and 12''. These are joined and steadied by cross frame C on the top, as shown in Fig. 1.

55 The filling machine as shown here has four cylinders, which number is sufficient

for a high speed of filling. However, the machine may be adapted for six, eight or more or fewer cylinders. Rigidly fastened to the upper part of the shaft 3 is a heavy cylinder frame D, Fig. 1, shown in cross section. This frame carries the filling and measuring mechanism proper. Carried by this frame D are cylinders 13 and 13'; the other pair of cylinders not being shown are 60 at exact right angles to those shown.

Reciprocating vertically are pistons 14 and 14' driven by piston rods 15 and 15' fixed to brackets 16 and 16' which are fastened to slides 17 and 17'. These slides are 65 accurately fitted in the cylinder frame D and may be moved upwards or downwards by rollers 18 and 18' moving during the operation in the inclined track E. This inclined track E has an upper and lower section 70 which are held together by lugs 19, 19', 19'' and 19''. By means of these rollers, which are ball shaped, the pistons are forced to reciprocate during the revolution of the cylinder frame D, caused by shaft 3 and driving 75 mechanism.

The inclined track swivels around two trunnions 20 and 20', Fig. 3. These trunnions are fitted to those two of the main posts 12' and 12''' which are in alignment 80 parallel to the straight track section of the flexible carrier system, viz: 12' and 12'''. By means of screws 21 and 21' engaging these trunnions, the inclined track may be raised or lowered, and by means of steady- 85 ing clamps 22 and 22' on the other two posts 12 and 12'', the degree of inclination of this track E may be adjusted and permanently locked after adjustment. It is preferable 90 that the two elevating screws 21 and 21' should be connected by a sprocket chain not shown. Fig. 1, however, shows one of the 95 sprockets 38 and the hand wheel 39, and this connection is for the purpose of elevating and lowering both screws at the same time 100 so as to avoid jamming.

It is evident from the construction of the inclined track that all pistons will ascend during one half the revolution and descend during the other half of the revolution. Supposing that the filling machine as shown 105 in Figs. 1 and 3 is to move clockwise, then the highest point of the track E is at post 12 and the lowest at post 12''. The pistons, therefore, move upward during their travel 110 from post 12'' to post 12, and downwards from 12 to 12''.

Variously tilting the track E and adjustment up and down accordingly, will vary the stroke of the pistons, and, consequently, the amounts forced out thereby.

I will now describe the valve mechanism proper. The lower part of the cylinder frame D is closed by the cylinder bottom plate 23, Fig. 1, shown partly in enlarged cross section in Fig. 2, and in top view,

Fig. 4. This plate 23 is tightly screwed against the cylinder frame casting D and also the lower part of the cylinders so as to make a tight joint. This is done by bolts, the bolt holes 24 shown in detail, Fig. 4.

The cylinder bottom plate has an annular depending hub 25 shown in Fig. 2 and keyed to it by means of key 26 is spout plate 27. Between the two plates 23 and 27 is a main valve casting 28, Figs. 1 and 2, and this main

valve casting is shown in top view in Fig. 3. Cylinder bottom plate 23, which closes the bottom of the cylinders, has outlet holes 29, 29', 30 and 30' for the cylinders, Fig. 4.

These outlet holes have different distances from the center, 29 and 29' located in an outer circle, and 30 and 30' in an inner circle, opposing cylinders having these outlets at the same distance from the center. The openings in the spout plate of which one is marked in Fig. 2 by the numeral 31, are exactly underneath and corresponding with the openings in the cylinder bottom plate 23.

It will be seen from the foregoing description that cylinder bottom plate 23 and spout plate 27 revolve together, being keyed together by means of key 26, Fig. 2. The valve casting 28 is interposed between these two plates and remains stationary during operation, and by its peculiar and novel arrangement of the port ways, alternately connects and disconnects the cylinders with the filling spouts or the intake for the material. The different radial spacing of the inlet and discharge openings maintains the discharges distinct.

In Fig. 3, 32 is a supply opening in valve casting 28. It has the shape of a crescent. Integrally cast with the casting 28 is an inlet tube 33 which communicates with the intake opening 32. This intake opening 32 is open to the top but closed at the bottom as shown in Fig. 1 in cross section, while two other crescent shaped openings 34 and 35 in the other half of the valve casting 28 go all the way through it, so that the outlet of the cylinder can be connected with the spout as shown in Fig. 1.

During the ascent of the pistons their respective cylinders are always connected with the supply opening 32 and give access of the material to the cylinders. During the descent of the pistons they are respectively connected with the outlet openings 34 and 35 of the valve plate, and eject the material through these narrow crescent shaped open-

ings 34 and 35 of the bottom plate. There are two neutral solid places in the direction of the posts 12 and 12' and two of these spout openings are shown in dotted lines as standing under these neutral places. One spout opening shows through the inner crescent 34, while the other spout opening shows underneath the intake opening 32, and is therefore shown in dotted lines.

Valve casting 28, standing stationary, fits closely without play between bottom plate 23 and spout plate 27. An adjustment of plate 27 to casting 28 can be made by nut 36 on hub 25, shown in detail in Fig. 2, to make a liquid-tight joint yet allow easy running. Spout castings 37 are fastened at the lower part of the spout plate 28 to bring the outlet openings centrally over the tray centers. Nut 36 of Fig. 2 has a very long thread for the purpose of lowering the valve plate 28 and the spout plate 27 for the purpose of cleaning.

The neutral zone of the valve plate is at right angle to the general direction of the tray carrier system as in Fig. 3, not as shown in Fig. 1. The discharge of the cylinders is only while the tray revolves in the semicircular path around the main shaft 3 from post 12 to post 12'.

Having described my invention, what I claim and desire to secure by Letters Patent, is:

1. In a filling machine, a revolvable measuring cylinder having a port, a spout and a container-carrier revolving with said cylinder, a fixed member between said cylinder and said spout, having an inlet opening to said port during part of the revolution and having an outlet opening from said port to said spout during another part of the revolution, a piston in said cylinder to actuate substance through said port, and a fixed inclined circuitous track operatively related to said piston.

2. In a filling machine, a revolvable series of cylinders each having a port, spouts and container-carriers revolving with the respective cylinders, a fixed member between said cylinders and said spouts, having an inlet opening to said ports during part of the revolution and having an outlet opening from certain ones of said ports to the respective spouts during another part of the revolution, and having another outlet opening from other ones of said ports to their respective spouts during this other part of the revolution, pistons in the respective cylinders to actuate substance through said ports, and means for actuating said pistons incident to the revolution.

3. In a filling machine, a revolvable series of cylinders arranged around adjacent to the axis of revolution, each having a port, spouts and container-carriers revolving around adjacent to said axis with the respec-

- tive cylinders, fixed means between said cylinders and said spouts controlling inlet to said ports and outlet from said ports to said spouts, pistons in the respective cylinders to actuate substance through said ports, and a fixed inclined circuitous track operatively related to said pistons.
4. In a filling machine, a revolvable series of cylinders arranged around adjacent to the axis of revolution, each having a port, spouts and container-carriers revolving around adjacent to said axis with the respective cylinders, fixed means between said cylinders and said spouts controlling inlet to said ports and outlet from said ports to said spouts, pistons in the respective cylinders to actuate substance through said ports, a fixed inclined circuitous track extending around said series of cylinders, and means connected to the respective pistons, movably mounted radially outside said series of cylinders, and operatively engaging with said track.
5. In a filling machine, rotary means comprising a cylinder adjacent to the axis of said means and a piston in said cylinder, and an inclined circuitous track around said rotary means, radially outward from said cylinder, an operative connection to said piston, engaging with said track to actuate said piston incident to rotation of said rotary means, and trunnions for said track, diametrically opposite to each other, on which said track swings to vary the stroke of the piston, the arrangement of said track radially outward from the cylinder permitting a compact construction of said machine together with a relatively great length of track to afford a relatively low angle of inclination thereof, for minimizing friction and wear of the operative connection.
6. In a filling machine, rotary means comprising a cylinder and a piston in said cylinder, an inclined circuitous track, an operative connection to said piston, engaging with said track to actuate said piston incident to rotation of said rotary means, and trunnions for said track, diametrically opposite to each other, on which said track swing to vary the stroke of said piston.
7. In a filling machine, a revolvable series of cylinders each having a port, certain ports being farther from the center of revolution than others, spouts revolving with the respective cylinders, fixed means between said cylinders and said spouts, having an inlet opening to said ports during part of the revolution, and having outlet openings at different distances from the center of revolution opening from the ports at the different distances from said center to respective ones of said spouts during another part of said revolution, pistons in the respective cylinders to actuate substance through said ports, and means for operating said pistons incident to the revolution.
8. In a filling machine, rotary means comprising a cylinder and a piston in said cylinder reciprocating substantially parallel with the axis of rotation of said rotary means, and a stationary valve plate relatively to which said cylinder is rotated, having an inlet port and an outlet port, each extending partly around said axis, said cylinder having a port communicating with the respective valve-plate ports intermittently incident to the relative rotation, the stationary condition of said valve plate permitting it to have its inlet port fixedly connected with an extraneous source of supply without an opening to the atmosphere between said valve-plate inlet port and said source of supply.
9. In a filling machine, a revolvable series of cylinders arranged around adjacent to the axis of revolution, spouts revolving around adjacent to said axis with the respective cylinders, fixed means between said cylinders and said spouts, admitting substance to said cylinders and controlling outlet from said cylinders to their respective spouts, pistons in the respective cylinders, means for operating said pistons incident to the revolution, a sprocket remote from said axis, a sprocket on said axis, and an endless series of container-carriers carried by said sprockets and revolving with the respective cylinders and spouts around adjacent to said axis.
10. In a filling machine, a revolvable series of cylinders arranged around adjacent to the axis of revolution, spouts revolving around adjacent to said axis with the respective cylinders, fixed means between said cylinders and said spouts, controlling inlet to said cylinders and outlet therefrom to the respective spouts, pistons in the respective cylinders, a fixed inclined circuitous track extending around said series of cylinders, means connected to the respective pistons and operatively engaging with said track, a sprocket remote from said axis, a sprocket on said axis, and an endless series of container-carriers carried by said sprockets and revolving with the respective cylinders and spouts around adjacent to said axis.

KARL KIEFER.
